UNITED STATES PATENT OFFICE.

STEPHEN RICHARD, JR., OF SOUTHBRIDGE, MASSACHUSETTS.

DESIGN FOR A KNIFE-HANDLE.

49,548.

Specification for Design.

Patented Aug. 22, 1916.

Application filed June 24, 1916. Serial No. 105,749. Term of patent 14 years.

To all whom it may concern:

Be it known that I, STEPHEN RICHARD, Jr., residing at Southbridge, in the county of Worcester and State of Massachusetts, have invented a new, original, and ornamental Design for a Knife-Handle, of which the following is a specification, reference being had to the accompanying drawing, forming part thereof.

Figure 1 is a perspective view of a knife handle looking at one side and end. Fig. 2

is a similar view of the handle looking at the opposite side and end. Fig. 3 is a central cross section of the handle.

I claim:

The ornamental design for a knife handle, as shown.

STEPHEN RICHARD, JR.

Witnesses:

ALBERT C. ST. ONGR,
LOUIS O. RIEUTORD.
